UNITED STATES PATENT OFFICE.

JAMES A. KLEES, OF READING, PENNSYLVANIA, ASSIGNOR TO THE KEYSTONE WAGON COMPANY, OF SAME PLACE.

DUMPING-WAGON.

SPECIFICATION forming part of Letters Patent No. 449,265, dated March 31, 1891.

Application filed November 22, 1890. Serial No. 372,819. (No model.)

To all whom it may concern:

Be it known that I, JAMES A. KLEES, a citizen of the United States, residing at Reading, in the county of Berks, State of Pennsylvania, have invented certain Improvements in Dumping-Wagons, of which the following is a specification.

Heretofore dumping-wagons have been constructed in which the wagon body or bed has been raised by means of elevating-arms pivoted at one end to the running gear or frame and at the other to the movable bed, and the connection between the bed and the frame has been so arranged as to either elevate the bed bodily, or either end of it independently or in succession.

The main object of my invention is to provide an improved construction whereby the wagon-bed may be raised by the continued operation of a single mechanism to the most advantageous heights and angles possible for different conditions. In dumping coal, for instance, the height to which it is advisable to raise the bed varies greatly. Where the cellar-hole is in the pavement but a short distance from the curb, it is unnecessary to raise the rear of the bed at all, and the front need only be lifted to secure a proper angle for dumping. Where the cellar-opening is on the ordinary building-line, it is usually necessary to raise the bed at both ends, but not to so great a height as is necessary where the cellar-opening is set back to more than the ordinary distance from the curb or where it is at an elevation. By means of my improved construction the front of the wagon alone is first raised until a proper angle for quick delivery to a short distance is reached. By continuing to operate the same lifting mechanism the rear end of the bed begins to rise, without, however, discontinuing the elevation of the front, so that the bed may be raised bodily to the extreme limit provided for.

The invention is more fully described in connection with the accompanying drawings, illustrating a preferred construction, and is specifically pointed out in the claims.

Figure 1 is a side elevation of a portion of a dumping-wagon, showing the application of my invention thereto. Fig. 2 is a similar

view showing the wagon-bed in elevated position.

A represents the frame of the running-gear to which the wagon body or bed B is movably connected by means of elevating-arms D, one 55 on either side of the wagon, the rear end of which is pivoted to the frame A at a point d behind the back axle C, while its forward end is pivoted to the bed B at a point d' forward of its normal center of gravity b'. As a means 60 of lifting the forward end of the elevating-bars and with them the bed B, I have represented them as provided with segment-rack extensions d², united with the main arm by a brace d³, curved to clear the axle C, in front 65 of which they are lowered with the wagon-bed, the rack gears with a pinion 5, forming part of a multiplying gear 1 2 3 4 5, secured to one side of the frame and operated by a crank G. It is evident, however, that other 70 well-known mechanism may be readily substituted, if preferred.

At a point c of the frame B is pivoted on each side e a stay-bar E, the forward end e' of which rides loosely in a carrier F, forming 75 part of the wagon-bed. To the rear end of the frame is secured a locking device H, consisting, as shown, of a folding arm, which is perforated to adjustably engage a projection b² on the wagon-bed. 8c

In Fig. 1 the wagon-bed is shown in its normal position, resting directly on the frame A. The forward ends e' of the stay-bars E are loosely supported in the carriers F, and the locking-arm H is folded against the side of 85 the frame at the rear. Upon turning the crank G the wagon-bed B is raised by the arm D; but as its connecting-point d' is forward of the center of the bed the rear portion overbalances the forward portion, so that the bed tends to turn on the point of suspension d', thus raising the forward portion, while the rear end keeps at its lowest point, as indicated by the dotted lines in Fig. 1. The free ends of the bars E are carried upward with the forward end of the bed, riding freely in the carriers F, which allow them sufficient longitudinal movement to reach the height indicated by said dotted lines without restraint. At this point, however, the move- 95 100

ment of the ends *e'* of the stay-bars *F* with relation to the bed *B* is stopped by the end *f* of the carriers *F*, and the continued operation of the crank *G* will evidently raise not only 5 the front of the bed, but the rear also, and the latter the more rapidly, inasmuch as the front can only raise thereafter as much as will be effected by the movement on the pivotal points *e* resulting from the horizontal movement of the bed as it swings on the pivotal centers *d* of the lifting-arms. It is evident, therefore, that while both front and rear are now raised the latter is constantly gaining on the former, so that as the height from the 15 frame increases the angle of the bed decreases, as is shown in Fig. 2, where the bed is represented in full lines, at about its maximum height, and in dotted lines at a less height, the angle of the bed thus slowly decreasing from the maximum angle (shown in dotted lines in Fig. 1) as the total height increases. On consideration it will be seen that this is exactly what is required in service, as the angle must necessarily be sacrificed, where the point to be reached by the 25 delivery-chute is at a considerable distance or elevation, while at nearer or lower points the advantage of a greater incline is secured. In other words, the height to which it is practicable to raise the bed being limited, the angle or incline must be sacrificed, as the limit of its capacity for delivery is approached.

It will be noticed that by my improved construction I can therefore secure the best attainable angles for different elevations automatically, no adjustment of angle whatever being required but the continued operation of a single crank raising the bed to practically the most advantageous position for any given 30 height from the lowest to the maximum. The proportions and location of parts may of course be readily varied, so as to change the angles more or less rapidly, as desired.

The locking mechanism *H* (shown in the 35 drawings at the rear of the frame) is provided to maintain the wagon-bed at the angles selected for dumping, inasmuch as the forward end is apt to overbalance the rear after a portion of the load has been removed from the 40 latter unless the bed is locked until the whole load is discharged.

Having thus fully described my invention, I do not limit myself to the particular con-

struction specifically described and illustrated; but

What I claim is—

1. A dumping-wagon provided with an elevating arm or arms and a pivoted stay operating in connection therewith, substantially as described, whereby the wagon-bed is elevated automatically, first at the front and thereafter at front and back simultaneously, by the continued operation of said arm, substantially as set forth.

2. In a dumping-wagon having elevating- 65 arms pivoted to the wagon-bed at a point forward of its center, mechanism for lifting said arms, and pivoted stays having their free ends loosely carried for a limited distance by the front portion of the wagon-bed, whereby said 70 front portion is first raised a limited distance alone and thereafter the whole body by the continued operation of said lifting mechanism, substantially as set forth.

3. In a dumping-wagon, the combination, 75 with the frame, of the movable bed connected therewith by elevating-bars pivoted at their rear ends near the rear of the frame and at their front ends to the bed forward of its center, and the stays pivoted at their rear 80 ends to the frame and having their forward ends loosely carried for a limited distance by the forward end of the bed and adapted to serve thereafter as a fulcrum for elevating the rear end, substantially as set forth.

4. In a dumping-wagon having an elevating-arm pivoted to the wagon-bed at a point forward of its center and mechanism for lifting said arm, the pivoted stays having their free ends carried for a limited distance by the 90 front end of the wagon-bed, and a locking mechanism to prevent tilting of said bed when raised, substantially as set forth.

5. In a dumping-wagon, the combination, 95 with the frame *A* and movable bed *B*, of elevating-arms *D*, multiple gearing for operating said arms, pivoted stays *E*, carriers *F* for said arms, and a locking mechanism *H*, all arranged and adapted to operate substantially as set forth.

In testimony whereof I affix my signature in presence of two witnesses.

JAMES A. KLEES.
